UNITED STATES PATENT OFFICE.

JOHN A. OLSON, OF CLEVELAND, OHIO, ASSIGNOR TO S-P MANUFACTURING COMPANY, OF CLEVELAND, OHIO, A CORPORATION OF OHIO.

CHUCK.

Application filed May 27, 1922. Serial No. 564,164.

This invention relates to chucks, particularly those of the automatically operated type.

One object of the invention is to construct a chuck, of the general type illustrated in my Patent No. 1,455,351, wherein the structure is simplified, and the cost of construction of the chuck materially decreased without sacrificing the advantages possessed by the previous type.

Another object is to construct a chuck having means for positively actuating the clamping members throughout substantially their entire stroke without lost motion or back lash and for maintaining the clamping members in clamping position while permitting movement of the actuating means.

Another object is to construct a chuck body having a central opening and slots for clamping members radiating therefrom and provided with reinforcing means adjacent to the central opening.

Another object is to provide in a chuck having a face portion in which is formed a central opening and slots radiating therefrom, means for strengthening and reinforcing the face portion, for excluding dirt from the interior of the chuck, for furnishing a bearing for the slidable means for actuating clamping members and a bearing engaged on opposite sides by the clamping members.

Other objects will appear and be pointed out hereinafter.

In the drawing accompanying and forming a part of this specification:

Fig. 1 is a front elevation of one form of chuck constructed in accordance with my invention.

Fig. 2 is a vertical cross-sectional view taken on line 2—2 of Fig. 1.

Fig. 3 is a fragmentary, top plan view taken on line 3—3 of Fig. 1.

Figs. 4 and 5 are respectively front and side elevations of the lever carrying member.

Fig. 6 is a diagrammatic representation of the relative positions of the lever and lever actuating member at either end of their strokes, and

Fig. 7 is a front end elevation of the lever actuating member.

In the drawings, wherein for purposes of illustrating my invention I have shown one embodiment of my invention, numeral 1 indicates a body member, comprising a circular

disc-like face portion 2, and a cylindrical flange 3, extending therefrom at the periphery of the face portion, and being provided with a central opening 2^a and radial openings 2^b extending from opening 2^a toward the outer edge of the face portion 2 for clamping members. At the center of face portion 2, and about opening 2^a is formed an upstanding circular rib 4, provided with a guideway or bearing surface 5. Between rib 4 and flange 3 are formed substantially parallel upstanding ribs 6, preferably arranged in pairs, and equally spaced on either side of openings 2^b.

Parallel with the face of portion 2, and arranged radially with respect to the face portion and opening 2^b are a plurality of grooves and tongues 7 and 8 respectively which are adapted to receive correspondingly formed clamping members consisting of jaws 9, and jaw slides 10. Between the meeting faces 11, of the jaws 9, and slides 10, is located an exteriorly threaded screw 12, which bears against end abutments in slides 10 and engages with threads on the jaws 9, thus operatively securing together the members 9 and 10 so that they function as a unit in the chuck.

Adjustment of the screw serves to move the jaws with respect to the slides 10, and in this manner to position the jaws to receive work blanks of various sizes the position of slides 10 in the body member being dependent upon levers 17, later to be described.

On the rear side of body member 1, is mounted a plurality of segmental lever carrying members, each consisting of a plate 14, and upstanding ribs 15, through which passes a pivot pin 16. On the pin 16, and between ribs 15, a lever 17 is pivotally mounted. This lever carrying member, is preferably secured to body member 1, between a pair of ribs 6, and fastened thereto by suitable securing means such as cap screws 18. Wide swinging movement of levers 17 is provided for by suitably recessing jaw slides 10 and plate 14 as indicated respectively at 13 and 13^a.

The ends of levers 17, adjacent to the pivot 16, are provided with projections 19, preferably in the form of teeth adapted to engage 105 with corresponding recesses 20, in the jaw slide 10. One or more projections 19, may be provided and in this modification I have

shown two such projections, the purpose being to provide an enlarged bearing surface in contact with the slides 10, whereby the latter may be actuated under varying loads without liability of breakage. The opposite end of levers 17, are preferably bifurcated having thus formed two projections 21^a, 21^b with a curved surface intervening. The rear edge of projection 21^a is also relieved substantially 10 as shown, for a purpose later to be described.

Slidably mounted in guideway or bearing 5, in the central rib 4, of body member 1, is a cylindrical member 22, having formed on its outer surface a plurality of projections or 15 cams to engage with the projections 21^a and 21^b of lever 17. This member 22, is adapted to be secured to suitable power actuating means such, for example, as a pneumatic plunger (not shown) and for this purpose is 20 provided with an opening 23, through which a headed bolt 24, passes and is secured thereto by a nut 25. The projections 26, which are formed by milling chordal slots or grooves 27 and 28, on the outer surface of member 22 25 preferably correspond in number to the number of levers in the chuck and are formed at substantially right angles thereto thus affording a broad area of contact with the levers. Each projection or cam 26, is prefer- 30 ably provided with a cam surface 26^a of varying curvature merging into a substantially flat portion 26^b near the top thereof, and a surface 26^c which may be of varying curvature or otherwise as may be desired. The rear 35 walls of grooves 27 are relieved to correspond with the rear edge of projection 21^a of lever 17, thus permitting a relatively long stroke of members 22, 17, 9 and 10.

As shown, member 22, is hollowed out as at 40 29 and a flanged dust bushing 30, is inserted therein and secured to the rear side of face portion 2 at the inner ends of each part of the face portion between the slots 2^b, as by rivets 31. Member 22 preferably has bearing 45 contact on its surface 29 with the exterior surface of bushing 30. This combination and arrangement of parts not only serves to exclude dirt, turnings, etc., from the interior of the chuck and contact therein with the 50 moving chuck parts but also serves greatly to strengthen the chuck at its center. Member 30 being secured to the face portion 2 adjacent the opening 2^a bridges the radial slots for the clamping members and tends 55 to distribute to the whole face portion 2 any strains imposed at one or more points thereof, thereby strengthening and rendering the face portion substantially rigid. Additional strength and rigidity is conferred on the face 60 portion 2 by the close fitting contact of the member 22 in body member 1 and about member 30, since strains tending to distort the face portion 2 will be transmitted through member 22 to and resisted by the entire body member.

65 The several clamping members preferably

have bearing engagement at all times with the front and rear surfaces of the flange 32 of member 30, the flange extending into the clamping members throughout substantially the entire stroke of the members as shown 70 in Fig. 2. In the form of members herein shown the opening in the clamping member for reception of flange 32 lies between the members 9 and 10. Inasmuch as member 10 has its meeting face 11 bored to receive screw 75 12, and therefore would present a relatively small bearing area for contact with flange 32, a filler plate 33 is secured near the inner end of the slide member, as shown in Fig. 2, and engages over an enlarged area with the 80 flange.

The operation of my improved chuck is substantially as follows: After the jaws 9, have been adjusted to the work blank which is to be held thereby, as may be done by turning screws 12, the power operating means is applied to cylindrical member 22, through bolt 24, thus causing the member to move rearwardly in the chuck. The levers 17 pivot about pin 16, due to the engagement of the 90 projections 21^a and 21^b thereof with cams 26 on the cylindrical member 22, teeth 19 on the opposite end of lever 17 actuating the clamping member comprising jaw slides 10 and jaws 9 toward the clamping position. As member 22, continues to move rearwardly the rear projection 21^a, on lever 17, moves up on the surface 26^a, the rate of movement of the lever continually decreasing, due to the decreasing pitch of the cam, until the projection 21^a, reaches the flattened surface 26^b. These 95 relative positions are shown clearly in Fig. 6. After projection 21^a, of lever 17, has reached the flattened portion of projections 26, no further movement of the lever results until the member 22, has moved an additional distance and projection 21^a comes into contact with the top of projections 26. It will be evident that the levers 17, are held stationary or 100 locked in position by the flattened surface 26^b of cams 26, since, to effect a movement of the levers in the opposite direction due to back lash by the jaws 9, forward movement of member 22, is necessary. As will appear from 105 reference to Fig. 6 where movement of lever 17 from a dotted line position into the solid line position is shown, movement of the levers out of clamping position results in radially inward movement of projections 21^a and in 110 gripping member 22 therebetween unless the latter is suitably moved. By reason of the flattened surface on cam 26, member 22, is permitted to move rearwardly an additional distance independently of levers 17, while the latter are held stationary or in clamping 115 position. The approximate extent of such movement of member 22, independent of lever 17, is illustrated in dotted lines in Fig. 6, where the front projection 21^b is spaced from cam 26. Before levers 17 are actuated out 120 125 130

of clamping position cam 26 moves forward to engage front projection 21^a.

Obviously the clamping members herein shown as consisting of members 9 and 10 may 5 be formed as a single element.

It will be seen from the drawings and the foregoing description that the projections 21^a and 21^b engage with both the opposite surfaces 26^a and 26^c of the projection 26 throughout substantially the entire stroke of the clamping members, the projection 21^b being out of contact with surface 26^c only when the clamping members are in clamping condition. In this manner I avoid all lost motion between the lever 17 and member 22 which could result in relative movement of the parts due to back lash.

Having thus described my invention in detail and shown one practical embodiment 20 thereof so that those skilled in the art may be enabled to practice the invention, what I desire to secure by Letters Patent is defined in what is claimed, it being understood that various modifications of the herein-described 25 parts may be made without departing from the spirit of my invention.

What is claimed is:

1. In a chuck, in combination, a body member having a peripheral flange, a centrally arranged rib having a guideway formed therein, pairs of ribs integral with the said peripheral flange and the said central rib, clamping members slidably mounted in the body member, a segmental plate provided 35 with parallel flanges and secured to each pair of ribs, a lever pivoted between the flanges on each plate, and engaging with the clamping members, and a cylindrical member slidably mounted in the said guideway and 40 adapted to actuate the said levers and clamping members.

2. In a chuck in combination, a body member having a central guideway, radially arranged clamping members slidably mounted 45 to reciprocate in the said body, levers engaging with the said clamping members to actuate the latter into and out of work clamping position and to lock the said clamping members in work clamping position, a cylindrical member reciprocably mounted in the 50 said guideway and having a plurality of exterior chordal projections each provided with oppositely disposed curved sides and a flat top surface therebetween, the said levers 55 each engaging both curved side surfaces of their respective projections throughout substantially the entire stroke of the clamping members and engaging with the said flat surface when the clamping members are substantially stationary in clamping position.

3. In a chuck, in combination, a body member having a plurality of clamping members and a cylindrical member slidably mounted 60 therein, a plurality of lever carrying members removably secured to the said body mem-

ber each comprising a segmental plate having upstanding substantially parallel ribs, a level pivotally mounted between the ribs of each of the said lever carrying members, the levers operatively engaging at one end with 70 the said cylindrical member and at the other end with the said clamping members.

4. In a chuck, in combination, a body member comprising a face portion having rearwardly extending ribs and flanges forming 75 cavities open to the rear of the face portion, plates forming closures for certain of the said cavities, ribs on each of the said plates, a lever pivoted between the said ribs of each plate, jaw slides in the body member and a 80 reciprocable member mounted centrally of the body member, the said levers each operatively engaging a jaw slide at one end and the reciprocable member at the other end.

5. In a chuck, in combination, a body member, a plurality of units removably secured thereto, each unit comprising a plate provided with ribs, a pivot pin mounted in the ribs and a lever pivoted between the ribs on the 85 said pin, jaw slides and jaws each engaging 90 one end of a lever and an actuating member engaging the other end of each lever.

6. In a chuck in combination, a body member provided with a face portion having radial slots intersecting with a central opening, a tubular member having a flange at one end, the said flange engaging the rear side of the face portions adjacent to the central opening and bridging the radial slots, the said flange being secured directly to the 95 inner end of each segmental part of the face portion between the slots by means passing through the said face portions and flange 100 clamping members slidable in the slots and engaging opposite sides of the said flange 105 throughout substantially their entire stroke, an annular bearing wall spaced apart from the outer surface of the said tubular member, a slidable cylindrical member having close fitting engagement simultaneously with 110 the said annular wall and the said tubular member and means engaging the cylindrical member to reciprocate the said clamping members.

7. In a chuck in combination, a chuck body 115 comprising a disc like face having a peripheral flange, the said face having a central opening therethrough and slots therethrough radiating from the central opening toward the outer edge of the face, an annular reinforcing member engaging the rear side of the 120 face adjacent to the central opening, bridging the said slots and secured directly to the inner ends of each of the segmental portions of the face between the slots by securing means passing through the said face and reinforcing member, clamping members 125 mounted to reciprocate in each of the said slots, the said clamping members engaging both the front and the rear surfaces of the 130

said annular member throughout substantially their entire stroke, and means for reciprocating the said clamping members.

8. In a chuck in combination, a chuck body comprising a disc like face having a peripheral flange, the face having a central opening therethrough and slots therethrough radiating from the central opening to the outer edge of the face, a tubular bushing 10 within the chuck body having an outer bearing surface and a reinforcing end flange, the said flange engaging the rear side of the said face, bridging the said slots and being secured directly to the inner end of each of 15 the segmental portions of the face between the slots by rivets passing through the said face and the flange of the bushing, clamping members mounted to reciprocate in each of the said slots and engaging with both the 20 front and rear surfaces of the said annular member throughout substantially their entire stroke, a cylindrical member having close fitting engagement with the outer bearing surface of the said bushing, and means 25 engaging the cylindrical member and the clamping members to reciprocate the latter when the former is moved.

9. In a chuck in combination, a body member having a disc like face provided with a central opening and slots radiating therefrom, spaced circular flanges integral with the face adjacent to the central opening and to the periphery of the face, substantially parallel webs arranged in pairs and integral 30 with the said face and flanges, clamping members slidable in the said slots, a lever 35 engaging each clamping member to actuate the same, a plurality of lever carrying mem-

bers each secured to a pair of said ribs and pivotally supporting a lever between the ribs, 40 and means for actuating the levers.

10. In a chuck in combination, comprising a face portion having a central opening, slots radiating from the central opening and spaced inner and outer annular flanges on 45 one side of the face portion disposed adjacent to the inner and outer peripheries, a reinforcing annular member secured directly to the segmental face portions defined by the radiating slots by members passing through the said face portions and reinforcing member at a plurality of points adjacent to the central opening and spaced apart from the said inner flange, substantially parallel webs on opposite sides of each of said slots integral with the face portion and the said flanges, clamping members slidable in the slots and means between the said webs for actuating the said clamping members.

11. The combination of a body having 60 radially arranged guide ways, slides in said guide ways, jaws secured to said slides, bell crank levers mounted in the body and engaging with said slides, one arm of each of 65 said levers projecting inwardly and having oppositely disposed cam faces, a slidable member having projections for engagement with said inner ends of the levers for actuating the same, means for preventing lost motion between the projections and cams, and 70 means for reciprocating said slidable member.

In testimony whereof, I hereunto affix my signature.

JOHN A. OLSON.
